DESIGN FOR A PORTABLE LAMP GUARD OR SIMILAR ARTICLE

Charles J. Hoffman, York, Pa.

Application May 16, 1944, Serial No. 113,608

Term of patent 14 years

(Cl. D48—16)

To all whom it may concern:

Be it known that I, Charles J. Hoffman, a citizen of the United States of America, residing at York, in the county of York and Commonwealth of Pennsylvania, have invented a new, original, and ornamental Design for a Portable Lamp Guard or Similar Article, of which the following is a specification, reference being had to the accompanying drawing, forming part thereof, wherein

Fig. 1 is a top plan view of a portable guard or similar article embodying my new design;

Fig. 2 is a side elevational view of the same;
Fig. 3 is an end elevational view of the same, looking at the end shown at the left in Figs. 1 and 2 and on an enlarged scale; and

Fig. 4 is an end elevational view of the same, looking at the opposite end and on the same scale as Fig. 3.

I claim:

The ornamental design for a portable lamp guard or similar article, as shown.

CHARLES J. HOFFMAN.
